UNITED STATES PATENT OFFICE.

AMBROSE HAROLD ROSENTHAL, OF BROOKLYN, NEW YORK.

BUCKLE.

1,090,415.

Specification of Letters Patent. Patented Mar. 17, 1914.

Application filed July 2, 1913. Serial No. 776,895.

To all whom it may concern:

Be it known that I, AMBROSE HAROLD ROSENTHAL, a citizen of the United States of America, residing at 1701 Pitkin avenue, 5 Brooklyn, in the county of Kings and State of New York, have invented certain new and useful Improvements in Buckles, of which the following is a specification.

My invention relates generally to buckles, 10 and may be applied to buckles for various uses, such as shoe buckles, belt and sash buckles, ornamental buckles and the like.

The object of my invention is to provide a novel form of buckle, the base portion of 15 which is preferably flexible and adapted for ornamentation by embroidery, the sewing of precious or imitation stones thereon, and in other ways.

Another object is to provide a greatly 20 simplified construction, of slighty appearance, and fairly strong and durable in construction.

It is to be understood that the buckle may take a great many forms, but for simplicity 25 of description only one such form or configuration has been shown in the accompanying drawing, wherein—

Figure 1 is a top plan view of my improved buckle; Fig. 2 a bottom plan view thereof; 30 Fig. 3 a perspective view of the base member of the buckle; Fig. 4 a similar view of the frame or metallic portion of the buckle.

In the practical adaptation of the invention I provide a suitably shaped base member 35 10, which as shown in the drawing may be elliptical, and is preferably composed of a suitably stiffened fabric, such as buckram, sufficiently flexible to allow the same to be bent.

40 To the base 10, I attach in a suitable manner the frame or metallic buckle portion, which is clearly disclosed in Fig. 4, and as there shown comprises the lateral parallel

arms 11, connected by the cross bar 12, which is preferably arched or elevated above the 45 plane of the parallel arms 11. The curvature of the bar 12 from the arms 11 is indicated at 13.

The arms 11 are provided at each end with sharpened ends or points 14 which are 50 turned at right angles to the plane of the bars 11, and are adapted to be inserted through the fabric 10 and then clenched so as to hold the metal structure firmly yet 55 removably on the base 10.

The metal structure is preferably of such character as to be capable of bending to some extent without breaking, and as the base member 10 is flexible, the entire structure may be shaped to adapt it to various 60 uses.

In practice, when the buckle is used in connection with a sash or ladies' belt, one end of the belt is attached, as by sewing, to the flexible base member 10, and the free 65 end of the belt is carried under the cross bar 12 and is there attached as by a bow knot or in any other desired manner.

What I claim is:—

As a new article of manufacture, a buckle 70 comprising a centrally open flexible base member, and a metallic frame adapted for attachment to said base member, said frame comprising a pair of elongated parallel arms each thereof having a point at each end 75 turned at right angles to the plane of the arm and adapted for engagement with said base member, and an arched cross bar formed integrally with said arms intermediate their ends. 80

In testimony whereof I have affixed my signature in presence of two witnesses.

AMBROSE HAROLD ROSENTHAL.

Witnesses:

OTTO MUNK,
CLARICE FRANCK.
